METHOD AND APPARATUS FOR GENERATING AND DETECTING IMPULSES

Original Filed March 23, 1918

FIG. 1.

FIG. 2.

INVENTOR=

Reginald A. Fessenden

By *Frank J. Hayes* ATTORNEYS.

UNITED STATES PATENT OFFICE

REGINALD A. FESSENDEN, OF CHESTNUT HILL, MASSACHUSETTS, ASSIGNOR TO SUB-MARINE SIGNAL COMPANY, OF PORTLAND, MAINE, A CORPORATION OF MAINE

METHOD AND APPARATUS FOR GENERATING AND DETECTING IMPULSES

Original application filed March 23, 1918, Serial No. 224,288. Patent No. 1,501,105, dated July 15, 1924.
Divided and this application filed May 21, 1924. Serial No. 714,899.

My invention relates to methods and apparatus for generating and detecting impulses; and more particularly to producing electrical effects or impulses by mechanical means, and 5 mechanical effects or impulses by electrical means; and still more particularly to the transmission and detection of sounds, more especially telephonic, and phonographic sounds. Increased efficiency, convenience, 10 simplicity, accuracy, freedom from disturbance, are its principal objects.

Fig. 1 shows diagrammatically means for producing an electrical indication by mechanically straining a magnetic wire, the 15 strain being produced by sound waves.

Fig. 2 shows diagrammatically means for producing a sound from a piano by the reverse action, i. e. the creating of an impulse or sound by electrical means. It also shows the 20 means applied to a piano for producing an electrical effect by mechanical strain.

This application is a division, so far as the parts which are common, of my U. S. application Serial Number 224,288, filed March 23rd, 25 1918, Patent No. 1,501,105, issued July 15, 1924, and of my application Serial Number 531,166; filed Jan. 23rd, 1922, the latter a division of an earlier case.

In Figure 1, 6 is a box having two opposite 30 ends formed of the diaphragms 7, 9. The ends of a wire 8 are attached to these diaphragms 7, 9, and the wire 8 is preferably made of some magnetic material, preferably very soft iron or nickel. 11 is a magnetizing 35 coil for magnetizing the wire 8, and 12 is a source of continuous current, though an alternating current source may be used. 10 is a second coil wound over the wire 8 and concentric with 11 and the terminals of the wire 40 10 are connected with the electric circuits as shown.

20 is a similar box, 19 being a similar wire, and 21 and 22 similar coils to 10 and 11, and 23 is a source of voltage similar to 12. As 45 this box is not used for sending and receiving but merely for balancing, diaphragms similar to 7, 9, are omitted in this box.

24 is a source of alternating current and the alternating current from the upper brush 50 flows up till it reaches the junction of the

primaries 14, 15, when it divides and one half flows through the primary 14, the condenser 13 and coil 10, and back again to the other brush of 24. The other half flows through the primary 15, condenser 16, coil 21, to the other brush of 24. 55

In operation the current from the source 24 flows through the divided circuits, and the primaries 14, 15 being wound so as to act oppositely on the secondary 17, no current is produced in the secondary 17 and no sound in the telephone receiver 18, so long as the two circuits are balanced. 60

As soon, however, as a sound travelling through the medium in which the box is immersed strikes the diaphragms 9, 7, the wire 8 is put in vibration and its magnetism is altered and the circuit is thrown out of balance and a sound is heard in the telephone receiver 18. 70

While a simple form of magnetic detector is here shewn, I have found that any of the well known forms of magnetic detector used for wireless telegraphy, for example those invented by applicant, may be used provided 75 that they are re-arranged and their construction so altered that the compressional waves to be detected set the magnetic circuit in vibration, and consequently I do not limit myself to this specific construction here 80 shewn.

Applicant's invention of the wireless telephone (Trans. Amer. Inst. Elect. Eng. July 1908 and U. S. Pat. 706,747, Sept. 29th, 1901) has now come into extensive use, but at present there is much distortion, both in the "pick-up" of the sounds to be transmitted, at the sending station; and in the reproduction at the receiving station; and there is much trouble from "atmospheric" and disturbing noises due to other causes; the loudness of the sound transmitted varies with the position of the actors on the stage, in vaudeville and other performances; and when reproduced the sound is loud close up 95 to the loud speaker and fainter at a distance, in the ratio of the square of the distance; and there is an un-natural quality about the re-production. In the making and re-production of phonograph records sim- 100

ilar difficulties are met with, except that in place of "atmospheric" there is the "scratching" of the needle.

These, and other difficulties are overcome by applicant's "area source" of sound production shown in U. S. Patents No. 1,277,562, filed Feb. 28, 1917, issued Sept. 3, 1918; No. 1,213,176, filed June 27, 1916, issued Jan. 23, 1917; No. 1,212,202, filed May 12, 1916, issued Jan. 16, 1917; No. 1,319,521, filed June 8, 1917, issued Oct. 20, 1919, and others, and more especially by the forms shown and described herein and in an application divided herefrom and about to be filed.

In Fig. 2 one form is shewn. Here 40 is the sounding board of a piano, which is constructed in the usual manner, well known in the art, except that between the tuning pegs 41, 42 there is stretched a nickel wire, 43, or one of other magnetizable material, 43. Upon this is wound a layer of enameled copper wire, 44, so that the whole has the appearance of the ordinary wound piano wire. 23 is a source of current, as before, and 45 is 25 a two way double pole switch for connecting 44 to the receiver when it is desired to transmit the sounds emitted by the piano when played upon in the usual manner; or for connecting to the transmitter when it is 30 desired that the piano should act as a loud speaker (for applicant has discovered that it is possible for a piano to so act, and better than any loud speaker now known to the art).

The "tonogen" type where, as shown in Fig. 35 2, the vibration is produced by the lengthening and shortening of the nickel (or iron or other magnetizable material) wire when its magnetization is altered by the transmitter currents, is especially useful in the case of 40 deaf or partially deaf people, who can be made to hear when such a wire as shewn at 43, 44 of Fig. 2 is held between their teeth and transmitter currents passed. The arm may be otherwise shaped if desired.

The vibration generating elements shewn in Figure 2 are conveniently attachable, as shown, to any musical instrument as to a banjo, mandolin, etc. They may also be attached to the tops of hotel tables, to plate 50 glass windows, etc. and to reflectors of lamps. The nickel wire wound with enamelled wire is very convenient, and is conveniently used doubled so as to form a complete magnetic circuit. In Fig. 2 the steel sounding board and steel pins complete the magnetic circuit. Where a stringed instrument is used as in Fig. 2 means may be attached for changing the natural resonant periods simultaneously, 60 by means well known in the art. It is advantageous as has been found by applicant, to pick up violin music by a violin used as pick up, and to use a violin as loud speaker, and to use pianos for piano music, though 65 this is not essential as a piano loud-speaker

will reproduce voice and violin with astonishing fidelity. Applicant having discovered that, contrary to the heretofore universally accepted doctrine, consonants, as well as vowels, can be perfectly transmitted and reproduced, by this means, by these instruments. Many other uses of the devices shewn will suggest themselves.

It will be noted that the method herein described and claimed is fundamentally different from any of the previously known methods of utilizing magnetostriction. In the previous methods the magnetism of the core when altered by a mechanical strain only gave one single impulse corresponding to that magnetic strain and if the magnetic strain was kept on for an hour there would be no further electrical impulse produced beyond that occurring during the fraction of a second while the mechanical strain was being applied. Also the energy of the electrical impulse produced was necessarily only a fraction of the energy of the mechanical stress applied. In applicant's method the change in permeability produced by the mechanical strain permanently affects, so long as it continues, the flow of a fluctuating or alternating current in the electrical circuit linked with the ferro-magnetic core. Consequently the variation in the energy delivered by the alternating current persists so long as the mechanical strain is maintained, i. e. electrical impulses are continually produced for it may be hours, so long as the core continues strained.

Also the effect is or may be many millions of times greater because in applicant's method the energy is not derived from the mechanical stress but from the energy of the alternating current circuit, the mechanical stress merely acting as a throttler or valve turner to govern or determine the amount of the alternating current energy flowing through the circuit.

Applicant has found that a much increased effect is obtained by making the magnetic core above described out of a single elongated crystal of ferro-magnetic material, both when used as a receiver and as a transmitter, and as a generator, but this is not claimed herein as it is claimed and more fully described in another application.

I claim:

1. A circuit for transmitting electrical impulses in accordance with mechanical variations comprising a normally balanced electrical circuit, means for impressing upon the balanced sections of said circuit alternating current of a suitable frequency, means for unbalancing said circuit by varying the permeability of a magnetic core forming a part of one balanced section by the mechanical forces exerted on said core, and means associated with said circuit for transmitting said electrical impulse.

2. A circuit for transmitting electrical impulses in accordance with mechanical variations comprising a normally balanced electrical circuit, means for impressing upon the balanced sections of said circuit alternating current of a suitable frequency, means for unbalancing said circuit by varying the permeability of a ferro-magnetic core forming a part of one balanced section by the mechanical forces exerted on said core, and means associated with said circuit for transmitting said electrical impulse. 6 70
3. A circuit for transmitting electrical impulses in accordance with mechanical variations comprising a pair of normally balanced shunt circuits, at least one having a sound responsive current varying device, means for impressing a suitable alternating carrier current upon said shunt circuits, a transformer having balanced primary windings connected one in each shunt circuit and the secondary connected in circuit to transmit electric impulses corresponding to the mechanical variations of the sound responsive device. 15 80
4. A circuit for transmitting electrical impulses in accordance with mechanical variations comprising a pair of normally balanced shunt circuits, a transformer having a plurality of primary windings connected in series 20 85
- 30 in said shunt circuits and a secondary for transmitting the electric impulses, means for impressing an alternating current on the balanced circuit and means included in one of said shunt circuits for unbalancing said circuit comprising a sound responsive current varying device having a ferro-magnetic core connected in said circuit. 90
5. A circuit for amplifying compressional wave impulses, including an electromagnetic sound responsive device having a ferro-magnetic core whose permeability varies in accordance with the compressional waves impressed on the sound responsive device, a second electromagnetic device for normally 40 100
- 45 balancing electrically the first electromagnetic device when not responsive to compressional waves, and means for impressing a suitable alternating current upon said electromagnetic devices and means for transmitting the unbalanced electric wave produced by the response of the sound responsive device. 105
6. A circuit for amplifying compressional waves, including a plurality of normally balanced windings having ferro-magnetic cores, 50 110
- 55 means for impressing an alternating carrier current upon said windings, means for electrically unbalancing said windings by varying the permeability of one of them in accordance with the compressional waves, and means 115
- 60 for transmitting the unbalanced component of the electric wave. 120
7. Means for transmitting compressional wave impulses, including a sound responsive device having a pair of diaphragms responsive to sound waves, a ferro-magnetic core 65 125
- 130
- whose permeability is varied by the action of the sound waves on the diaphragms, and a normally balanced circuit including said sound responsive device and a local alternating carrier current supply whereby the action of said sound responsive device will modulate said carrier current supply in accordance therewith. 75
8. Means for transmitting compressional waves, including a casing having a diaphragm at opposite sides, a ferro-magnetic core adapted to receive mechanical stresses corresponding to the compressional waves acting on said diaphragm, and means operated thereby for modulating a local carrier source in accordance with the compressional waves. 80
